DEVICE FOR USE IN GRINDING VALVES

Harry Wolf Kulp and Martin Cope Dellinger,
Lancaster, Pa.

Application January 30, 1931, Serial No. 512,411

16 Claims. (Cl. 51—262)

This invention relates to a combined unitary valve centering and jumping device for use in connection with the grinding of valves wherein the valve-stem has an enlarged lower end.

5 The primary object of the invention is to provide as a single unitary structure a means or temporary bearing or bushing for centering the valve in association with means for raising the valve as the pressure thereon is removed to jump 10 the valve in the grinding operation; to provide a pair of semi-cylindrical cooperating centering bushings permanently pivotally connected together by means of a pair of yokes or straps; to provide a unitary device of this character comprising a pair of pivotally mounted cooperating semi-cylindrical bushings so mounted as to swing 15 toward each other under the influence of gravity and operatively engaged by the bore in the engine block to hold the same in proper centering 20 cooperating relation during the grinding operation of the valve; to provide in such a structure means for limiting the movement of the semi-cylindrical bushing sections in swinging about their pivot points beyond a position parallel to 25 the axis of the unit as a whole; to provide means irrespective of the bushing sections and irrespective of the pivot pins for connecting the yoke bars or plates to each other; and to provide means limiting the movement of the unit as a whole 30 downward in the bore of the engine block.

In some makes of automobiles, particularly the Model A Ford, the valve-stem is guided by a split bushing and has an enlargement, such as F, at its lower end so that in order to entirely 35 remove the valve and its stem from the engine block it is necessary to entirely remove the split bushing. This makes the valve grinding operation tedious and somewhat difficult even for the experienced mechanic because of the need to remove the bushings every time the valve is inspected 40 to see if the grinding operation has been completed and for this reason there is a demand for a simple unitary device which may be used as a centering means, which may be easily withdrawn and reinserted without appreciable risk 45 of the dropping of any part thereof, and also which shall have a spring means for jumping the valve to facilitate the grinding operation.

The present invention has been developed with 50 the foregoing considerations and objects in view.

In this application we show and describe only the preferred embodiment of our invention simply by way of illustration of the practice thereof, as by law required. However, we are well aware 55 that our invention is capable of other and dif-

ferent embodiments and that the various details thereof may be modified in a number of different ways, all without departing from our said invention; therefore, the drawing and description herein are to be considered as merely illustrative and not as exclusive.

In the accompanying drawing:

Figure 1 represents a fragmentary sectional view of an engine block, a valve raised from its seat and with one of the unitary devices embodying our invention applied about the valve-stem and disposed in the valve-stem bearing bore and having its jumping spring bearing against the lower face of the valve E;

Figure 2, an elevation of a valve with its stem 70 and with a device embodying our invention shown in vertical cross section on line 2—2 of Figure 4, looking in the direction of the arrows, in the course of being applied thereto, and in dotted lines in the position which the semi-cylindrical bushings 1 assume with relation to their pivot pins 2 and with relation to each other when the greatest diameter of the enlargement F passes between the upper portions of said sections 75 1;

Figure 3, a vertical cross sectional view on the 80 line 3—3 of Figure 4, looking in the direction of the arrows;

Figure 4, a top plan view of the unit with the spring 4 omitted.

Referring now in detail to the drawing, A, 85 designates the engine block; B, the valve port or chambers; C, the valve-stem bushing bore; D, the valve-stem having the valve E carried on the top thereof and having its lower end provided with an enlargement or cone F as illustrated.

90 Preferably our invention will be embodied in a device having two externally semi-cylindrical internally longitudinally centrally grooved members 1, permanently associated together in such manner as to have relative movement with relation to each other whereby their adjacent faces may be moved apart to permit the passage between them of the enlargement F. Such association may be by any suitable means. In the embodiment illustrated such association is by 95 means of two yoke bars or plates extending preferably parallel to each other and respectively engaging the outer faces of both of the members 1 and their laterally offset shoulders 1a, so that the shoulder 1a of each member 1 is interposed 100 between the respective end portions of the plates 3 and a pivot pin 2 extending through each of the registering end portions of the plates 3 and the respective intervening laterally offset portion 1a 105 of the respective members 1 serves to pivotally 110

connect the members 1 together for swinging movement about their respective pivot pins 2 toward and from each other, and the ends of the pins 2 being upset or riveted over establish a permanent inseparable connection between these parts.

Preferably each member 1 will be formed with a radially extending enlargement or stop shoulder 1' to engage upon the upper face of the bottom 10 of the valve port or bore B to limit the downward movement of the bushing members 1, that is of the device as a whole, in the bore C. Said shoulders will preferably be semi-annular so as to together constitute an annular shoulder, but 15 this is not of any particular importance and said shoulder or shoulders may be of any shape and area so long as they function to the desired end.

Each said member 1 will preferably be provided 20 with a stop shoulder 1b to engage the opposed lower edge of one of the yoke bars 3 when the said member 1 has been swung about its pivot pin 2 to the point where said member extends parallel to the axis of the unit as a whole, whereby 25 rigidity of the device or unit as a whole when applied about the valve-stem D with the edges of the members 1 in engagement, will be greatly increased.

A jumper spring 4 will preferably be provided 30 and will preferably be permanently associated with some one or more of the other parts of the device in such manner as to be interposed between the valve E and the upper portions of the members 1. Preferably said spring will be connected in some suitable manner to one or more 35 of the yoke plates or bars 3, preferably being connected to both of said plates or yoke bars 3. Preferably the said yoke bars 3 are connected together irrespective of the pivot pins 2 and preferably such connection will be by means serving 40 to brace and center said bars or yokes 3 with relation to each other. In the embodiment illustrated the respective plates 3 are provided with lugs or ears 5 which are bent over about the lower helix of the spring to tightly and rigidly grasp 45 the spring and connect the same to each of said yoke bars or plates 3 and the upper edge portion of each said plate or yoke bar 3 adjacent each side of the lug 5 and in transverse registry with each other is cut out as at 6, as shown in Figure 50 4, to accommodate a portion of the circle of the lower helix of the spring to thereby center and brace the yoke bars or plates 3 with respect to each other and irrespective of the pivot pins 2. This construction results not only in bracing and 55 centering the plates 3 with relation to each other but also serves to center and rigidly hold the spring 4 in position and results in a very desirable structure of a firm and lasting nature.

Of course the inner opposed faces of the members 1 will be formed with opposed longitudinally extending grooves semi-cylindrical in cross section and together defining a cylindrical bore of such size as to snugly receive and accommodate the valve-stem D.

60 While the provision of the spring 4 for jumping the valve is highly desirable, obviously it is not essential to the centering operation and it may be dispensed with while still retaining our invention, considered in its broader aspects, this being illustrated in Figure 4.

In the use of the instant invention the valve-stem D is inserted downward through the helical spring 4, until it engages the upper end faces of the members 1, as illustrated in dotted lines in 75 Figure 2, when the valve stem D will be moved

further downward through the device of this invention until the spring 4 engages the underface of the valve E. All of this may be accomplished by simply taking hold of the spring 4 between the thumb and forefinger of one hand, and with the other hand placing the enlarged end F of the valve-stem D against the upper ends of the members 1 and releasing the valve-stem when its weight will be sufficient to spread the members 1 to permit the passage of the valve-stem or if not a slight shove will suffice. With the device thus applied to the valve-stem, the members 1 will be swung toward each other by hand to lie parallel to and against the valve-stem D with their edges in engagement when the valve-stem D with the unitary device of this invention applied thereto is to be inserted in the engine block, as illustrated in Figure 1.

The adjacent portions of the upper end faces of the members 1 may be downwardly curved as 90 illustrated in all the figures to give a cam action between the lower end of the enlargement F of the valve-stem D and the upper ends of said members 1 during the insertion of said stem D through the unitary device of this invention.

Also the lower end portions of the bushing members 1 may be downwardly and radially inwardly beveled to give a frusto conical contour to the lower portion of the composite split bushing to facilitate the entrance of the latter into 105 the upper end of the bore C in the engine block, all as is obvious.

Having thus described our invention, what we claim as new and desire to secure by Letters Patent is:

1. A valve-stem guide and valve lifter for use in grinding valves and comprising a plurality of relatively movable longitudinally extending sections through which the stem of the valve to be ground is guided, said sections cooperating to 110 together constitute a guiding body of a composite cross sectional external contour having portions lying on different points of a circle concentric with the axis of the body and being insertable into the bore of the engine block, means for connecting said sections together for relative movement in a transverse direction to permit the passage between them of an enlarged end portion of the guided valve-stem, said means comprising a pair of yoke bars applied on opposite sides of 115 the upper portions of said sections and with their extreme end portions in transverse registry and pivot pins extending through said end portions and the respective intervening upper end portions of the respective sections, said sections being formed with downwardly presented arcuate, 120 radially extending stop shoulders adapted to engage the engine block adjacent the bore thereof, and stop lugs formed on said sections respectively and so positioned as to engage one of said yoke bars when its respective section shall have been moved into position parallel to the axis of the device as a whole, in combination with a helical spring secured to the upper portion of each said yoke bar and adapted to engage the lower face 125 of the valve, each said yoke bar being formed with a lug bent around the lower helix of the spring, to firmly secure said yoke bars and spring together and each yoke bar having its upper edge portion cut out equi-distantly on opposite sides of said lug to accommodate an arcuate portion of said lower helix in said cut out portions and to afford a seat for the lower helix of the spring on the upper edge portions of said yoke bars respectively, and the extreme outer end walls of 130 said cut out portions serving to limit the radially 135

5. A valve-stem guide and valve lifter for use in grinding valves and comprising a plurality of relatively movable longitudinally extending sections through which the stem of the valve to be ground is guided, said sections cooperating to together constitute a guiding body insertable into the bore of the engine block, means for connecting said sections together for relative movement in a transverse direction to permit the passage between them of an enlarged end portion of the guided valve-stem, said means comprising a pair of yoke bars applied on opposite sides of the upper portions of said sections and with their extreme end portions in transverse registry and pivot pins extending through said end portions and the respective intervening upper end portions of the respective sections, and stops provided on said sections and adapted to engage the engine block adjacent the bore thereof, in combination with a helical spring secured to the upper portion of each said yoke bar and adapted to engage the lower face of the valve. 110
- 120 125 130 135 140 145 150
6. A valve-stem guide and valve lifter for use in grinding valves and comprising a plurality of relatively movable longitudinally extending sections through which the stem of the valve to be ground is guided, said sections cooperating to together constitute a guiding body insertable into the bore of the engine block and means for connecting said sections together for relative movement in a transverse direction to permit the passage between them of an enlarged end portion of the guided valve-stem, in combination with a helical spring disposed above, and connected to said means.
7. A valve-stem guide and valve lifter for use in grinding valves and comprising a pair of longitudinally extending sections adapted to fit in the bore of the engine block and to be held in definite relation to each other thereby and having their opposed inner faces longitudinally grooved in such cross sectional contour as to

guide a valve-stem interposed between said sections, said sections having laterally outwardly offset upper end portions, in combination with means for pivotally connecting said laterally offset upper end portions of said sections together for relative swinging movement toward and from each other in a plane parallel to the longitudinal central line of said sections.

8. In a device of the class described, a pair of 10 valve stem embracing members pivoted together on a transverse axis at their upper ends, said members comprising guide portions having semi-cylindrical outer surfaces and opposed semi-cylindrical grooves adapted snugly to fit a valve stem 15 inserted between the pivoted upper ends of said members.

9. In a device of the class described, a pair of 20 valve stem embracing members, said members comprising guide portions having opposed semi-cylindrical grooves and head portions having opposed grooves larger than those of the guide portions, and means pivotally connecting said members on a transverse axis at their head portions.

10. In a device of the class described, a pair 25 of substantially symmetrical members pivoted together on a transverse axis at their upper ends, the lower portions of said members being shaped for insertion into the valve stem guide bore of an engine and being provided with opposed semi-cylindrical grooves adapted to fit a valve stem 30 inserted between the pivoted upper ends of said members, the upper portions of said members being provided with opposed grooves larger than but forming continuations of the grooves of said 35 lower portions.

11. In a device of the class described, a pair of 40 substantially symmetrical members comprising lower portions shaped for downward insertion into the valve stem guide bore of an engine, said lower portions having opposed semi-cylindrical grooves, said members having enlarged head portions provided with opposed grooves adapted to accommodate and pass a valve stem extremity of greater diameter than the passage defined by the 45 semi-cylindrical grooves of the said lower portions, and means pivotally joining said head portions on a transverse axis.

12. In a device of the class described, a pair 50 of valve stem embracing members pivoted together on a transverse axis at their upper portions, the lower portions of said members being shaped for insertion into the valve stem guide bore of an engine and being provided with opposed grooves adapted snugly to fit the cylindrical portion of a valve stem, the upper portions of 55

said members being provided with opposed grooves constituting continuations of the grooves of the lower portions and being adapted to pass a valve stem extremity of greater diameter than the passage defined by the grooves of the said lower portions.

13. In a device of the class described, a pair of 80 valve stem embracing members pivoted together at their upper ends, said members comprising guide portions having semi-cylindrical outer surfaces and opposed semi-cylindrical grooves adapted snugly to fit a valve stem inserted between the pivoted upper ends of said members, and a valve unseating spring carried by the pivoted upper ends of said members irrespective of pivotal relation, and projecting upwardly therefrom.

14. A device of the class described comprising 85 a pair of substantially symmetrical valve stem guide members shaped for insertion into the valve stem guide bore of an engine and provided at their lower portions with opposed semi-cylindrical grooves adapted to embrace the cylindrical portion of a valve stem, said members being pivoted together on a transverse axis at their upper ends and having the opposed surfaces of their upper 90 portions conformed to pass a valve stem extremity of greater diameter than the passage defined by the opposed semi-cylindrical grooves of the said lower portions.

15. In a device of the class described, a pair of 100 valve stem embracing members pivoted together at their upper ends on a transverse axis, said members comprising guide portions having semi-cylindrical outer surfaces and opposed semi-cylindrical grooves adapted snugly to fit a valve stem 105 inserted between the pivoted upper ends of said members, and a valve unseating spring carried by the pivoted upper ends of said members, irrespective of pivotal relation, and projecting upwardly therefrom.

16. In a device of the class described, a pair of 110 valve stem embracing members pivoted together at their upper ends, on a transverse axis, said members comprising guide portions shaped to fit within the valve stem guide bore of an engine 115 and provided with opposed semi-cylindrical grooves adapted snugly to fit a valve stem inserted between the pivoted upper ends of said members, and a coiled valve unseating spring carried by and projecting upwardly from the upper ends of said members, the lowermost convolution of said spring being secured to said members in the vicinity of their pivotal connection.
